SPRUE-FORMING DEVICE

Peter L. Perazo, Oakland, Calif.

Application March 6, 1937, Serial No. 129,502

3 Claims: (Cl. 22—38)

The invention relates to a device for use in sand casting with a mold box or flask for providing sprues for the mold spaces while compacting the sand about a pattern.

5 An object of the invention is to provide an improved sprue punch which is arranged to resiliently bear against a pattern member for providing an open passage to the member.

10 Another object is to provide an improved sprue punch which is adapted to be removed from a sprue formed therewith with a minimum of contact with the sprue bore.

15 A further object is to provide a tubular sprue punch which is operative as a cutter and in which any packing of the core of molding sand received therein as the punch is applied is avoided.

20 Yet another object is the provision of an improved means for mounting a sprue punch on the squeeze board of a molding box or flask for its longitudinal adjustment for engaging patterns of different depths.

An added object is to provide an improved flask and squeeze board combination.

25 The invention possesses other objects and features of advantage, some of which, with the foregoing, will be set forth or be apparent in the following description of a typical embodiment thereof, and in the accompanying drawing, in which,

30 Figure 1 is a side elevation of a squeezer board carrying a pair of sprue punches embodying the present invention, said punches being shown as partly engaged in the molding sand in the upper, or cope, section of a molding flask which contains a pattern and is shown in section at the plane of the punches.

Figure 2 is an enlarged axial section of a sprue punch assembly of Figure 1, the view being taken at 2—2 in Figure 1.

40 Figure 3 is a fragmentary and partly sectional view showing a sprue punch assembly of Figure 1 having its punch engaging the pattern in the flask.

45 By way of illustration, the features of present invention are incorporated in casting apparatus which includes sprue punch assemblies mounted on a squeezer board 5 which is provided for compacting the molding sand 6 in a mold flask section 7 and about a pattern which engages against a match-plate 9 on which the flask section 7 rests. The flask section 7 is provided at its opposite ends with members 11 which receive pins 12 for simultaneous registration in openings through the match-plate 9, or in members 11 mounted on the lower flask section (not shown), for assuring an aligned registration of the flask section 7 with the match-plate or with the lower flask section. The pattern 8 may be that of an article to be cast in the section 7, or may provide a distributing gate

for castings to be produced therein or in an underlying flask section.

Openings 13 are provided transversely through the squeezer board 5, and basin pattern members 14 and 15 are mounted on the under face of the board with openings therethrough in alignment with the different openings 13. The members 14 and 15 may be of metal, are hollow from their board-engaging faces, and generally taper from said faces. Like punches 17 extend freely through the different openings 16 for forming sprues in the sand of the mold as the sand is compacted beneath the squeezer board 5. The member 14 is of frusto-conical outline with the opening 16 thereof provided at its lower face, 15 while the member 15 is more or less oval in plan with the opening 16 thereof provided through the larger portion of its lower face. It will be understood that the member 15 shapes a pouring basin for the passage provided by its punch, while the member 14 shapes a funnel-like upper end for the passage provided by its punch, the latter passage being utilizable as a passage for molten metal to a mold cavity of the flask or as an air vent for such a cavity; for convenience, both of said passages are hereinafter referred to as sprues.

It will now be noted that each punch 17 comprises a tubular element having the portion thereof which extends below a basin pattern 14 or 15 externally tapered whereby the punch may wedgedly engage the sand for insuring a particularly compacted condition of the sand adjacent the sprue bore as the punch is forced into the sand for registration with the pattern 8, and providing for a simultaneous release of the punch from all portions of the sprue bore as its axial withdrawal is started. The interior bore 18 of the punch tapers to an inturned and sharpened edge 19 at its free advance end whereby the sand pressed within the bore 18 as the punch is pushed downwardly to the pattern 8 may remain relatively uncompacted within the punch and yet is retained for its removal with the punch. By reason of the core of sand thus provided within the punch 17, the latter may also, on occasion, be referred to as a sprue cutter.

Each tubular punch 17 is mounted on a longitudinally expanded helical spring 21 which is coaxial with the punch and is fixed to a flat ring member 22 having its central opening aligned with the spring bore. A U-shaped bracket 23 is mounted on the upper side of the board 5 with its intermediate portion 24 parallel to the board and having a central perforation 25 in alignment with the punch axis. Mutually parallel bolts or screws 26 are threadedly engaged through the bracket portion 24 transversely thereof and at opposite sides of the perforation 25, and are swivelled in the ring 22 to provide for the longitudinally adjusted positioning of the punch and spring assem-

bly as a unit with respect to the board, and while the punch is engaged in the sand of a mold.

The punch 17 and its associated spring 21 are also preferably engaged for relative adjustment longitudinally thereof. Accordingly, and as shown, the exterior of the upper punch portion may be formed with a spiral thread groove having the pitch of the lower coils of the spring 21 and arranged to threadedly receive said coils whereby the punch is adjustably mounted within the lower spring portion. As illustrated, the lower spring portion which receives the upper punch portion is of reduced diameter whereby the same number of spring coils may be constantly free of the punch; in this manner, the operative length of the spring is not changed when the punch is adjusted with respect to the spring.

It will now be noted that the squeezer board 5 is shaped and adapted to slidably fit within the bore defined between the walls 27 of the flask section 7 in the general manner of a piston, and is provided with cleats 28 which extend above the punch-carrying brackets 23 whereby the upper press plate (not shown) of a usual press may engage across the cleats for forcing the punch assembly on the board into the sand of the section 7 while compacting the sand beneath the board; as an alternative, the cleats 28 might be free or be mounted on the press plate without affecting the use of the press or the operation of the squeeze board 5.

At and around the periphery of its sand-engaging face, the squeezer board 5 is preferably provided with a protruding flange or rim 29 having its exposed face more or less rounded; as shown, the flange 29 comprises half-round molding. The flange 29 is operative to prevent a lateral movement of the sand from beneath the board as the latter is pressed against the sand.

For providing connected sprue and mold openings in the present flask in connection with the pattern 8 on the plate 9, the distances from the top flask plane to the points of the pattern 8 which are to be disposed in the lines of the punches 17 are measured, and the punches are adjusted in their described mountings on the squeezer board 5 to extend for slightly greater distances from the top plane of the board than said measured distances. Since patterns in the flask may vary somewhat in depth as measured from the plate 9, both described devices for adjusting the spacing of the advance end of a punch with respect to the board may of necessity be jointly utilized for disposing the punch end as desired for providing its required contact with the pattern.

Having the punch, or punches, adjusted as required, and the molding sand placed in unpacked condition in the flask section around and above the pattern to the approximate level of the upper flask plane, the squeezer board is now deposited vertically upon the sand in the flask for effecting the entry of the punches 17 into the sand while aligning the board with the bore of the flask. A subsequent engagement of the assembly between the upper and lower thrust plates of a press, and the operation of the press may force the board 5 into the upper end of the flask section to compress the sand while forcing the punches therethrough for engagement with the pattern, the compressive movement of the board being stopped, in the present instance, when the outer board face is flush with the top flask plane.

It will now be particularly noted that a punch 17 engaging a pattern in the flask has been thereby forced inwardly against the resistance of its spring 21 whereby it resiliently engages the pattern with its bottom edge preferably engaging flat against an upper pattern face thereat with a pressure which varies with its imposed inward movement with respect to the board 5. Since the punch is positively restrained against lateral displacement only at the point where it may engage the side of an opening 16 in a basin pattern 14 or 15, some displacement of the punch with respect to the line of its normal position is permitted as it is advanced toward the pattern, this being desirable to overcome any unbalanced resistance which the punch may encounter as it is being pushed toward the pattern, whereby to minimize the effect of friction and to insure the flat and sealed engagement of the punch end with the pattern surface engaged by it. If the pressure bearing of an installed punch with the pattern is not as required or desired, adjustment may be made while the board is in place by suitable manipulation of the adjustment bolts 26.

When the sprue and mold spaces have been formed by the punches and patterns, a vertically upright removal of the squeeze board and the elements thereon may be effected, and a subsequent inversion of the board permits a gravity discharge of the sand from within the punches. After the pattern 8 has been removed from the under side of the flask section, the latter may then be combined with a previously prepared lower flask section (not shown) for completing the mold space for use in casting in a usual way.

From the foregoing description taken in connection with the accompanying drawing, the advantages of the construction and method of use will be readily understood by those skilled in the art to which this invention appertains. While I have described the features and principles of operation of a structure which I now consider to be a preferred embodiment of my invention, I desire to have it understood that the present showing is primarily illustrative, and that such changes may be made, when desired, as fall within the scope of the following claims.

I claim:

1. In combination with a squeeze board for a molding flask, an helical compression spring, a sprue punch threadedly engaged with the coils of an end portion of the spring axially thereof for its axial adjustment with respect to the engaged spring portion to adjustably vary the distance of the punch point from the extremity of the engaged spring portion, and means unitarily attaching the other spring end to the board to dispose the spring in perpendicular relation thereto.

2. A structure in accordance with claim 1 wherein the base portion of the sprue punch is externally threaded for its threaded and frictional engagement with the bore of the spring portion thereat, and the extending sprue portion is tapered to its working point.

3. A structure in accordance with claim 1 wherein the last means is adjustable to adjust the engaged spring end with respect to the working face of the board axially of the spring.

PETER L. PERAZO.
